United States Patent Office.

MAURICE FITZGIBBONS, OF NEW YORK, N. Y.

Letters Patent No. 87,334, dated March 2, 1869.

IMPROVED FUR-BOX.

The Schedule referred to in these Letters Patent and making part of the same

To all whom it may concern:

Be it known that I, MAURICE FITZGIBBONS, of the city, county, and State of New York, have invented a new and valuable Improvement in Fur-Boxes, for the protection and preservation of furs, fur garments, and other garments or wearing-apparel; and I do hereby declare that the following is a full, clear, and exact description of the construction and operation of the same, reference being had to the annexed drawings, making a part of this specification, and to the letters and figures of reference marked thereon.

My invention relates to boxes designed for holding and transporting furs, fur garments, &c.; and

It consists in new and effective means for protecting furs and fur garments against moths or other destructive insects.

The letter A, of the drawings, represents a quadrangular paper box, lined throughout with Spanish cedar, camphor, or other odorous wood veneering. On the drawing, this veneering is shown by the lines in red, marked B.

The letter C represents a circular recess, adapted to the size and shape of a lady's muff.

The recess is formed of paper or pasteboard, and lined with veneering of cedar, camphor, or other odorous wood.

The letter D is a recess, of the size and shape of the upper end of the box, veneered as aforesaid, and adapted to receive and hold a fur collar, or other like apparel.

The letter E is a lid, of paper, lined with veneering of cedar, camphor, or other odorous wood, hinged with

cloth, or otherwise, and arranged to fit closely upon the top of recess E.

The letter F represents a paper or pasteboard cover, that fits closely over the recess E, and enclosing the lid G.

An important novelty in my box consists in the fact that the paper or pasteboard constitutes the main or principal feature of the box, as this lining of veneer is only about one-hundredth of an inch in thickness, and is glued or pasted firmly to the paper body of the box. No shrinking or cracking is possible.

I am aware that it has long been known that several odorous woods are destructive to insects, or to which insects have an aversion, especially such insects as are destructive to furs and wool; and I am also aware that repositories have been made of other woods; and I do not claim either of these subjects as my own discovery or invention; but

What I do claim, as an article of manufacture, is—

The muff-box herein described, viz, when made of pasteboard, and lined with thin veneers of camphor or cedar-wood, to preserve the furs from moths, all substantially as described.

In testimony that I claim the above, I have hereunto subscribed my name, in the presence of two witnesses.

MAURICE FITZGIBBONS.
